UNITED STATES PATENT OFFICE.

PATRICK F. McCORMACK, OF WEST RUTLAND, VERMONT, ASSIGNOR, BY MESNE ASSIGNMENTS, TO SULLIVAN MACHINERY COMPANY, OF BOSTON, MASSACHUSETTS, A CORPORATION OF MASSACHUSETTS.

STONEWORKING-MACHINE.

1,133,233.

Specification of Letters Patent. Patented Mar. 23, 1915.

Application filed August 5, 1910. Serial No. 575,635.

To all whom it may concern:

Be it known that I, PATRICK F. McCORMACK, a citizen of the United States, and a resident of West Rutland, in the county of Rutland and State of Vermont, have invented an Improvement in Stoneworking-Machines, of which the following description, in connection with the accompanying drawings, is a specification, like letters on the drawings representing like parts.

This invention relates to stone working machines and more particularly to machines of the channeling type, the object of the present invention being to provide a simple channeling apparatus intended more particularly though not exclusively for cutting the corner of a channel groove or that portion which extends under an overlying side wall of a quarry.

Corner cutting has frequently been performed by pivotally mounting the tool standard of an ordinary track channeler upon the truck, and, with the truck fixed in position at the spot where the corner is to be cut, swinging the standard about its fixed pivot by means of the truck driving motor and by means of tool swinging mechanism especially provided for the purpose. This causes the cutting tools to cut along the arc of a circle and in so doing to reach in under the overhanging side wall of the quarry.

In the present embodiment of the invention, I am enabled to dispense with much of the mechanism heretofore required by reciprocatively moving the tool support, as, for example, the truck, while at the same time holding some part of the tool or tool support attached to an extraneous object, such as the track, so that the reciprocatory movement of the support causes the cutting devices to swing or move through a path reaching in under the quarry side wall.

The invention will be best understood by reference to the following description when taken in connection with the accompanying illustration of one specific embodiment thereof, while its scope will be more particularly pointed out in the appended claims.

In the drawings; Figure 1 is a plan view of a channeling machine embodying one form of my invention; and Fig. 2 is a front elevation of the channeling machine shown in Fig. 1.

Referring to the drawings, I have there illustrated my invention by embodiment in 55 a track channeler of common construction, the same consisting of the main truck or frame 1 mounted upon the truck wheels 2, the latter adapted to travel along track way 3 customarily laid along the quarry bottom. 60

As is usual in this class of devices, the truck is self propelled by a suitable motor, such, for example, as the steam or air engine 4, which is mounted upon the truck and adapted to drive the same through appropriate truck driving mechanism. Herein a common form of driving mechanism is employed, as follows: Connected to the crank shaft 5 of the engine is a beveled driving gear 6 meshing with the gears 7 and 8 loose 65 upon the countershaft 9, but adapted either one to be clutched thereto by the sliding clutch members 10 and 11 respectively. The latter are moved simultaneously by the slide rod 12 and lever 12^a, so that either gear 7 70 or 8 may be clutched at will to drive the countershaft 9, and therefore turn the latter in either direction.

The countershaft 9 carries the pinion 13 meshing with driving gear 14, the latter 80 secured to the truck driving shaft 15 which drives the axles 16 and wheels 2 through the worm gearing 17. By this mechanism the operator can drive the truck in either direction and reverse the same at will.

The machine illustrated is provided with the usual form of tool carrier or standard 85 18 mounted at the side of the truck, herein upon the standard carrying bracket 19, the latter being adapted to be adjustably positioned and clamped at either end of the truck upon the trunnion bar 20.

Any form or construction of channeling tool and motor may be employed, but herein I have illustrated a common form of air 95 channeling engine 21 having rigidly secured thereto cross head guides 22, the two constituting a sliding frame adjustable lengthwise the standard through the medium of the feed screw 23. Any suitable means may be 100 employed to turn the feed screw, but herein the upper end thereof is provided with a beveled gear 24 meshing with a pinion 25, the latter carried at the end of the telescopic shaft 26. The lower end of the shaft is provided with a pinion 27 meshing with beveled

gear 28, the latter adapted to be clutched at will either to the gear 29 or gear 30 by means of the sliding clutches 31 or 32. The gears 29 and 30 respectively mesh with the gears 7 and 8. The feed screw 23 may be turned in either direction or held at rest by shifting the clutches 31 and 32 to one position or another.

The tool feed actuating mechanism forms 10 no essential part of my invention and any form of tool feeding mechanism may be employed, or a hand feed if desired may be utilized.

To the piston rod 33 of the engine 21 is 15 secured the cross head 34 adapted to slide in the cross head guides 22 and having attached thereto the tool or tools 35 constituting the channel gang.

The described form of channeler may be 20 employed in the usual way in cutting the ordinary channel groove. That is to say, the standard may be clamped upright at either end of the truck, as represented in dotted lines in Fig. 2, one or more brace 25 members 56 (also shown in dotted lines) being employed to hold the standard rigid. When it is desired to cut the corner, however, the brace member or members 56 are removed and the standard which has a pivotal connection 37 to the bracket 19 is loosened so as to be free to turn about such pivotal connection. The truck is then arranged on the trackway with relation to the walls of the quarry in some such position as 30 is represented by dotted lines in Fig. 2, and there is jointed to some part of the tool carrier, preferably near the upper part of the standard as at 38, a link 39 or other suitable attachment member, the opposite end of 35 which has a jointed connection to some fixed extraneous object, such, for example, as the clamp 40 fixedly clamped to one of the rails just back of the truck. The clamp 40 is 40 easily detachable and can be readily applied 45 to a rail where desired when corner cutting is to be done. The position in which the clamp is placed in the first instance determines the throw of the cutting tool and standard and its adjustment to a different 50 position can be effected any time during a cutting operation to alter the throw.

With the parts arranged as shown in dotted lines in Fig. 2, the truck driving motor can be thrown into connection with 55 the truck driving mechanism by means of the lever 13 to advance the truck, just as in traversing the same for cutting the usual channeling groove. The truck then moves in toward the overhanging wall of the 60 quarry from the dotted line position shown in Fig. 2 to the full line position there shown carrying the pivotal support 37 of the standard along with it. The upper end of the standard, however, being attached to a fixed 65 extraneous point, the tool gang will swing

or move from the dotted line position shown to the full line position shown in Fig. 2, causing the cutting edges to describe a path suitable for cutting the corner. When the inward extreme limit of movement has been 70 reached, the truck driving mechanism can be reversed to swing the standard back to the dotted line position shown, this cycle of movements being repeated again and again and the tools being fed slowly forward by 75 means of the feed screw until the required depth of cut has been obtained.

It will be seen that by utilizing the main support, herein the truck, to move or swing the standard while holding the latter fixed, 80 or relatively so, by attachment to some extraneous point, the truck driving mechanism itself can be utilized to swing or move the tools for corner cutting as well as to move the truck for cutting in the open, thereby 85 eliminating much complicated mechanism.

By the term corner cutting I comprehend not only the cut under the overlying side wall of the quarry at the junction of the two side walls, but also the cut under such side 90 wall at any point thereof, the latter being sometimes termed "transverse cutting." It is obvious that this application of the invention is but one of many and that it is applicable in the form herein shown or in 95 modified forms thereof to many different uses.

While I have shown and described for purposes of illustration one specific embodiment of the invention, it is to be understood 100 that the latter is not limited to the details herein shown nor to the application of the invention herein illustrated, nor to the specific form of machine to which the same is shown and applied, but that extensive deviations may be made therefrom without departing from the spirit of the invention. 105

Claims:

1. In a channeling machine the combination with a percussive channeling tool having a cutting portion, of a main support on which said tool is held movable, mechanism for reciprocatively moving said main support, and means to hold said tool at one portion thereof by attachment to an extraneous 110 point, thereby to cause the movement of the support to move the cutting portion of said tool through a path suitable for corner cutting.

2. In a track channeler, the combination 120 with a truck, truck driving mechanism, a standard held movable on said truck, a channeling tool mounted on said standard, and means for connecting said standard at one portion thereof to an extraneous point while 125 operating said truck driving mechanism.

3. In a track channeler the combination 130 with a truck, truck driving mechanism, a reciprocatory channeler tool mounted for swinging movement upon the truck, and

means to swing the tool through movement of the truck.

4. In a channeler, the combination with a tool, a support on which the tool is pivoted, a connection to an extraneous point, and means for reciprocatively moving the support.

5. In a track channeler, the combination with a truck, a channeling tool mounted to swing on said truck, and connections between said tool and an extraneous point.

6. In a channeling machine, the combination with a truck, truck driving mechanism for moving said truck reciprocatively, a channeling tool mounted to swing on said truck, and a link for connecting said tool to the trackway.

7. In a track channeler, the combination with a truck, truck driving mechanism for driving the truck reciprocatively, a motor for actuating said truck driving mechanism, a channeling tool mounted on said truck, means for adjusting said tool to cut the ordinary channel groove while utilizing the truck driving mechanism, and means also to swing said tool for corner cutting through the medium of said truck driving mechanism.

8. In a stone working machine, the combination with a percussive cutting tool of a tool support on which the tool is mounted for swinging movement, a connection with a point extraneous to said support and means for causing relative movement between said point and said support.

9. In a stone working machine the combination with a percussive stone working tool of a movable tool-carrying member on which said tool is mounted, an extraneous member to which said tool carrier is relatively movable, said tool at one portion thereof being also secured to said extraneous member and means for causing relative reciprocating movement between the members to swing the tool while the latter is acting percussively to cut the stone.

10. In a channeling machine the combination with a main truck of a standard pivotally mounted thereon, a reciprocatory percussive channeling tool mounted on said standard, a feeding mechanism for feeding the tool forward on the standard, an extraneous object having connection to the standard, and truck driving means for causing movement of the truck relatively to the extraneous object to swing the tool through the channel cut during its reciprocatory percussive cutting movement.

11. In a channeling machine the combination with a truck of a standard movably mounted thereon, a reciprocatory percussive channeling tool mounted on said standard, an extraneous object, a connection between the standard and said object, and truck moving means for causing relative movement be-

tween the truck and extraneous object to cause the tool to swing through the channeling cut during its reciprocatory percussive cutting movement.

12. In a channeling machine the combination with a main support of a standard pivotally mounted thereon, a reciprocatory percussive tool on said standard, feeding means for feeding the tool on the standard, an extraneous object, a connection between the standard and said object, and means for moving the support relatively to the extraneous object to cause the tool to swing through the channel during its reciprocatory percussive cutting movement.

13. In a channeling machine, the combination with a main support of a standard movably mounted thereon, a reciprocatory percussive channeling tool mounted on the standard, an extraneous object, a connection between the standard and said object, and means for causing relative movement between the support and said object to cause the tool to sweep through the channel cut during its reciprocatory percussive cutting movement.

14. In a channeling machine the combination with a truck, of truck driving mechanism, a motor, truck reversing means, a standard mounted at the side of the truck and movable to either end thereof, a pivotal support, means to hold the standard fixed or to free the same for movement about said pivotal support, a reciprocatory cutting tool, an engine connected to drive said tool, a sliding frame on which the tool and engine are carried, said frame being movable on the standard toward or from the work, feeding means to advance or retract the frame, a member adapted to be clamped to the rails adjacent the truck and a link adapted to connect said member and a portion of said standard whereby when said truck is reciprocated the standard and cutting tool are caused to swing about their pivotal support on the truck.

15. In a channeling machine the combination with a truck, truck driving mechanism, a motor connected thereto, reversing means to reverse the motor driven movement of the truck, a standard mounted at the side of the truck and movable to either end thereof, means to hold the standard fixed or to free the same for swinging movement about its support on the truck, a percussive cutting tool and tool motor carried by the standard, means to adjust the motor on the standard toward or from the work and a connection between the standard and a fixed part of the trackway whereby the standard when freed for swinging movement is caused to swing about its support on the truck when the latter is reciprocatively driven on the trackway.

16. In a stone-working machine the com-

- bination with a percussive stone-working tool of a movable tool carrying member on which the said tool is mounted, an extraneous member to which said tool carrier is 5 relatively movable, a connection between one portion of said tool and said extraneous member, means for causing a relative reciprocating movement between the members to swing the tool while the latter is acting per-
- 10 cussively to cut the stone, and means for adjusting the connection of the tool to said extraneous member.
17. In a stone-working machine the combination with a movable support, a percussive stone-working tool mounted to swing upon said support, connections between said tool and an extraneous point, means for causing relative movement between said support and said point, and means for adjusting said connection.
18. The combination with the truck 1 of the standard 18, the motor 21, tool 35, pivotal support 37, and connections 39—40 between the standard and an extraneous point.
- 25 19. In a channeling machine, the combination with a tool carrier of a reciprocating channeling tool mounted for swinging movement upon the carrier, a tool swinging member extraneous to the carrier, a connection 30 between the tool swinging member and the tool, and means to impart a relative reciprocating movement to said tool and tool swinging member to swing the tool while the latter is percussively cutting the stone.
- 35 20. In a channeler, the combination with a tool, a support on which the tool is pivoted, a member extraneous to said support, a connection between said member and said tool, and means for imparting a relative motion 40 to said member and tool.
21. In a channeler, the combination with a tool carrier, a channeling tool mounted to swing on said carrier, a member extraneous to said carrier, a link connecting the tool 45 and said member, and means to impart a relative reciprocating motion to said carrier and member.
22. In a channeler, the combination with a main support, of a standard movably 50 mounted thereon, a reciprocatory, percussive channeling tool mounted on the standard, a member extraneous to said standard, a connection between said standard and said member, and means for imparting a relative motion to said standard and member to cause 55 the tool to sweep through the channel cut during its reciprocatory cutting movement.
23. In a channeler, the combination with a tool carrier, of a tool supporting member movably mounted thereon, a reciprocatory, 60 percussive, channeling tool mounted on the support, a member extraneous to said tool support, a connection between said members, a motor on said carrier, and power transmitting means between said motor and one 65 of said members to move one of said members and thereby cause movement of the tool.
24. The combination with a guiding and supporting frame, of a tool carrying member, an extraneous tool moving member, 70 means to impart a movement to one of said members, a tool pivoted on said tool carrying member, and means connecting said tool to said tool-moving member for utilizing said movement to cause said tool to swing 75 on its pivot.
25. The combination with a guiding and supporting frame, of a tool carrying member, an extraneous tool moving member, means to impart a reciprocatory movement 80 to one of said members, a tool pivoted on said tool carrying member, and means connecting said tool to said tool-moving member for utilizing said movement to cause said tool to oscillate. 85
26. The combination with a guiding and supporting frame, of a tool carrying member, an extraneous tool moving member, means to impart a movement to one of said members, a tool mounted for movement on 90 said tool carrying member, and means connecting said tool to said tool-moving member for utilizing said movement to cause said tool to move relatively to said tool carrying member. 95
- In testimony whereof, I have signed my name to this specification, in the presence of two subscribing witnesses.
